UNITED STATES PATENT OFFICE.

THOMAS H. BULLOCK, OF CLEVELAND, OHIO.

TYUERE.

SPECIFICATION forming part of Letters Patent No. 251,761, dated January 3, 1882.

Application filed May 14, 1881. (No model.)

To all whom it may concern:

Be it known that I, THOMAS H. BULLOCK, of Cleveland, in the county of Cuyahoga and State of Ohio, have invented certain new and useful Improvements in Tuyeres; and I do hereby declare the following to be a full, clear, and exact description of the invention, such as will enable others skilled in the art to which it pertains to make and use it, reference being had to the accompanying drawings, which form part of this specification.

My invention relates to tuyeres; and it consists in the peculiar construction of the valve of the same.

15 In the drawings, Figure 1 is a sectional elevation taken through the line of the blast-nozzle. Fig. 2 is a transverse section of the same.

A is a case or box, into which the blast-nozzle B enters.

20 C is the valve, which is made cam-shaped, as shown in Fig. 1.

D is the grate, which is formed concave on its lower side to accommodate the convex surface of the valve C.

25 E is a shaft, to which the valve C is fastened, and which serves as a means whereby the said valve is revolved. One end of this shaft E is provided with a handle, F, and a ratchet, a, and spring-pawl b, the object of the 30 ratchet and pawl being to hold the valve in the desired position. One side of the valve C is

cut away, so that when said valve is turned with that side uppermost the air will pass through the opening in the grate D with full force, as shown in Fig. 1; but as the valve is 35 revolved in the direction of the arrow, Fig. 1, the blast is cut off more and more, until it is finally cut off entirely by that part of the valve which is farthest from its axis having reached the opening in the grate D. 40

What I claim is—

1. In a tuyere, the combination, with the tuyere-grate, formed concave on its under side, of the tuyere-valve, constructed with a cam-shaped periphery in cross-section and cut away 45 on one side of its shaft, said valve being arranged to be forced snugly against the concave seat on the under side of the grate, substantially as set forth. 50

2. A tuyere-valve, the same being made cam-shaped in cross-section, in combination with the shaft E and its ratchets a and pawl b, all operating substantially as and for the purpose shown and described.

In testimony whereof I have signed my name 55 to this specification in the presence of two subscribing witnesses.

THOMAS H. BULLOCK.
